(57) **CLAIM**

The ornamental design for a combined dog waste bag dispenser and waste receptacle, as shown and described.

DESCRIPTION

FIG. 1 is a top front right side perspective view of the combined dog waste bag dispenser and waste receptacle, showing the waste bag dispenser in a closed position and the waste receptacle in a closed position, embodying my design; FIG. 2 is a top front right side perspective view of the combined dog waste bag dispenser and waste receptacle of FIG. 1, showing the waste bag dispenser in an open position and the waste receptacle in a closed position;

FIG. 3 is a top front right side perspective view of the combined dog waste bag dispenser and waste receptacle of FIG. 1, showing the waste bag dispenser in an open position and the waste receptacle in an open position;

FIG. 4 is a top plan view of the combined dog waste bag dispenser and waste receptacle of FIG. 1;

FIG. 5 is a left side elevational view of the combined dog waste bag dispenser and waste receptacle of FIG. 1;

FIG. 6 is a right side elevational view of the combined dog waste bag dispenser and waste receptacle of FIG. 1;

FIG. 7 is a front elevational view of the combined dog waste bag dispenser and waste receptacle of FIG. 1;

FIG. 8 is a back elevational view of the combined dog waste bag dispenser and waste receptacle of FIG. 1; and,

FIG. 9 is a bottom elevational view of the combined dog waste bag dispenser and waste receptacle of FIG. 1.
